UNITED STATES PATENT OFFICE.

WILLIAM P. AIKIN, OF WATERTOWN, NEW YORK, ASSIGNOR TO INTERNATIONAL BURE CORPORATION.

EXPANDING MANDREL.

1,270,089.

Specification of Letters Patent. Patented June 18, 1918.

Application filed December 10, 1917. Serial No. 206,511.

To all whom it may concern:

Be it known that I, WILLIAM P. AIKIN, a citizen of the United States, residing at Watertown, in the county of Jefferson and 5 State of New York, have invented certain new and useful Improvements in Expanding Mandrels; and I do hereby declare the following to be a full, clear, and exact description of the invention, such as will 10 enable others skilled in the art to which it appertains to make and use the same, reference being had to the accompanying drawings, and to the letters and figures of reference marked thereon, which form a part of 15 this specification.

This invention relates to new and useful improvements in mandrels for burs, for the purpose of redressing the surfaces of pulp grind-stones, and consists in the provision 20 of expanding means upon the mandrel for holding the bur securely in place thereon.

The present invention consists of various details of construction, combinations and arrangements of parts which will be herein- 25 after fully described, shown in the accompanying drawings and then specifically defined in the appended claims.

I illustrate my invention in the accompanying drawings which, with the letters 30 of reference marked thereon, form a part of this application and in which:

Figure 1 is a central sectional view through a mandrel and bur.

Fig. 2 is an end view, and

Fig. 3 is a view showing the parts disassembled.

Reference now being had to the details of the drawings by letter:

A and B designate two mandrel sections, 40 the former of which has an elongated shell portion C circumferentially threaded, and about which the section B, which is interiorly threaded, is adapted to be mounted. This section A is provided with a beveled 45 flange E, and F designates a cylindrical split ring, with an interior beveled portion H. Said ring F fits over the circumference of the mandrel section A and is adapted to have a wedging action against the beveled

50 flange E. The mandrel section B has a beveled shoulder N, and O designates a split ring similar to the ring F, having a beveled portion T, adapted to have a wedging action against the inclined shoulder upon the

section B. The adjacent ends of the two 55 ring sections are adapted to contact with each other as the mandrel sections are screwed together, thus serving to expand the rings and cause the circumferences thereof to frictionally engage the bore of the 60 bur. The outer face of the section B is provided with holes S, for the reception of a wrench whereby the section B may be turned. A roller bearing member K is placed within the bore of the mandrel sections and 65 forms a bearing therefor.

In assembling the parts, the mandrel section A is placed upon the base, provided with projecting prongs fitting the holes upon the end thereof and by applying a wrench 70 or other tool in the member B, the two mandrel sections may be tightened, so that the circumference of the split ring will frictionally engage the bore of the bur. The roller bearing is then inserted within the 75 mandrel sections, after which the roller bearing is placed upon the fork which is attached to, or is a part of, the pulp mill lathe, the fork having a pin M of a suitable size to hold the mandrel or bur. The operator will then screw the lathe up, until the bur comes in contact with the rapidly rotating grind stone, and which in turn causes the bur and mandrel to revolve rapidly in the opposite direction, leaving the imprint 85 on the surface of the grind stone corresponding approximately to the cut of the bur.

What I claim to be new is:—

1. An expanding mandrel for burs comprising two hollow sections having threaded connection with each other, and each having a cylindrical circumference with a flaring beveled flange portion at its outer end, split rings with their inner faces cylindrical, one mounted upon each section and adapted to engage the cylindrical circumference thereof, said rings having beveled portions adapted to have a wedging action against the beveled flanges of said sections, 100 and means upon one of said sections for limiting the lateral movement of the shell of a bur thereon.

2. An expanding mandrel for burs comprising two hollow sections having threaded connection with each other, and each having a cylindrical circumference with a flaring beveled flange portion at its outer end, split

rings with their inner faces cylindrical, one mounted upon each section and adapted to engage the cylindrical circumference thereof, said rings having beveled portions 5 adapted to have a wedging action against the beveled flanges of said sections, the beveled portion on the circumference of one of said sections terminating in a cylindrical shoulder adapted to be engaged by the shell

of a bur, and serving to limit the lateral 10 movement of the latter in one direction.

In testimony whereof I hereunto affix my signature in presence of two witnesses.

WILLIAM P. AIKIN.
